UNITED STATES PATENT OFFICE.

NATHAN I. BERGER, OF NEW YORK, N. Y., ASSIGNOR TO SANDOW TOOL CO. U. S. A., OF NEW YORK, N. Y., A CORPORATION OF NEW YORK.

DESIGN FOR PLATE FOR LIGHTING FIXTURE.

Application filed October 5, 1925. Serial No. 15,023. Term of patent 3½ years.

To all whom it may concern:

Be it known that I, NATHAN I. BERGER, a citizen of the United States, and a resident of the borough of Manhattan, city, county, and State of New York, whose post-office address is 396 Broadway, in the borough of Manhattan, city, county, and State of New York, have invented a new, original, and ornamental Design for Plate for Lighting Fixture, of which the following is a specifi-

cation, reference being had to the accompanying drawing, forming part thereof.

Figure 1 is a plan view of the plate for lighting fixture, showing my new design, and Figure 2 is a side view thereof.

I claim:

The ornamental design for plate for lighting fixture, as shown.

NATHAN I. BERGER.
